UNITED STATES PATENT OFFICE.

HORACE A. CARTER, OF NEEDHAM HEIGHTS, MASSACHUSETTS.

UNDERGARMENT.

1,199,347.

Specification of Letters Patent. Patented Sept. 26, 1916.

Application filed January 28, 1916. Serial No. 74,755.

To all whom it may concern:

Be it known that I, HORACE A. CARTER, a citizen of the United States, and a resident of Needham Heights, in the county of Norfolk and Commonwealth of Massachusetts, have invented an Improvement in Undergarments, of which the following description, in connection with the accompanying drawings, is a specification, like characters on the drawings representing like parts.

This invention relates to undergarments, which may be either of the union undergarment type or may be of the nether garment type. The garment is particularly intended for use by males.

In order that the principle of the invention may be readily understood, I have disclosed a single embodiment thereof in the accompanying drawings, wherein—

Figure 1 is a front elevation of a union undergarment embodying my invention; Fig. 2 is a rear elevation thereof; Fig. 3 is a plan view of certain gussets which may be and are preferably used in the formation of the garment; Fig. 4 is a view similar to Fig. 3 but representing said gussets as inserted in the garment; Fig. 5 is a front elevation of the garment upon the wearer; and Fig. 6 is a view, partially in front elevation and partially in vertical section, and representing the front of the garment, viewed from the inside thereof.

While I have selected for the purpose of illustration a union undergarment, it is to be understood that the invention may be applied to nether garments. While preferably the garment is a knitted one, obviously my invention may, in its broad aspect, be applied to a garment of woven or other suitable material. While the undergarment may be fashioned in any suitable manner, I preferably, and particularly in the case of a union undergarment, form the same with a body portion 1, arms 2, 2, integral therewith, and leg portions 3, 3 also integral therewith. I have represented the garment as having an opening 4 in the front, extending from the neck opening 5 substantially to the crotch portion of the garment. My invention may be applied to a union undergarment of the drop seat, the closed crotch, or other type.

In the ensuing description the terms "right" and "left" will be used in describing the portions of the garment with reference to the wearer, and not the observer.

In order to provide the proper fullness across the hips or thighs, and in order also to furnish a suitable opening at the back, if the garment be of the type herein illustrated, I preferably provide two gusset portions, respectively indicated at 6, 7, in Figs. 3 and 4, the gusset 6 being herein designated as the left-hand gusset because in practice the greater portion of its perimeter is seamed to the left-hand leg of the garment, and the gusset 7 being termed the right-hand gusset inasmuch as the greater portion of its perimeter is seamed to the right-hand leg of the garment. If the garment be a knitted one, which is in accordance with the preferred embodiment of my invention, the knitted wales extend longitudinally of the body, arms and legs, and also extend longitudinally of the gussets 6, 7.

The lateral edges 8, 9, 10, 11 of the gussets are preferably cut upon curved lines, which converge toward each other. Each gusset has a square upper end 12, 13, which in the garment are lapped past each other and secured to the body of the garment at the rear, as indicated in Fig. 2. The edge 9 of the gusset 6 and the edge 10 of the gusset 7 constitute the free edges of the garment at the rear. The edge 8 of the gusset 6 and the edge 11 of the gusset 7, which as previously described are preferably cut upon curved lines, are seamed to straight edges of the body portion of the garment, thus giving increased width across the hips and thighs of the wearer.

The garment embodying my invention is preferably, though not necessarily, of the closed crotch type, and in the formation of the gussets 6, 7, and in the application thereof to the garment I preferably provide each gusset 6, 7, with two gores, numbered respectively 14, 15, 16 and 17. The gore 14 of the left-hand gusset 6 constitutes a thigh-widening gore, and is attached along both its edges to the inside seam of the left leg, thus enlarging the diameter of the upper portion of that leg, and the gore 15 of the said left gusset constitutes in effect a suspensory-forming gore, to coöperate with certain parts hereinafter specified to provide a suspensory pocket. The said gore 15 is carried over and attached to the inside seam of the right leg just below or at the crotch, as indicated most clearly in Figs. 1, 4 and 5. As indicated most clearly in Fig. 3, the said gore 6 is provided with a widened extremity

18 which is seamed along its extent as described to the inside seam of the right leg. The gore 17 of the right gusset 7 is seamed along both its edges to the inside seam of the 5 right leg, thus enlarging the diameter of the upper portion of the leg, and the gore 16 constitutes a suspensory-forming gore and is carried across and seamed to the inside seam of the left leg at the upper portion 10 thereof just below or at the crotch. It will be observed that the gores 15, 16 of the gussets 6 and 7 differ slightly in shape, the gore 15 being broadened at its lower edge. If desired, however, and within the scope of 15 my invention, the two gores may be duplicates of each other.

The gores 15 and 16 are, in the complete garment, superimposed the one upon the other. Viewing Figs. 1 and 5, it will be observed that both of the suspensory-forming gores 15, 16 are positioned wholly at one and the same side of the axial line of the crotch, which may be defined as the median line of the garment or the front opening 4. The 25 upper ends of the said gores 15, 16 are superposed as described, and are secured to the upper edges of the legs wholly at one side of the said axial crotch line.

An important purpose of carrying the 30 gores 15, 16 past each other and securing them to the upper portions of the inside seams of the opposite legs is to provide a suspensory or support for the organs.

While my invention pertains and relates 35 particularly to and is embodied and comprehended in a garment having the characteristics hereinbefore described, I am not limited thereto inasmuch as for certain purposes the pocket-forming or body-adjusting strip 40 or strips hereinafter referred to may be employed upon other types of undergarments. The said strip or strips, however, peculiarly coöperate with a garment of the type described, that is, one wherein I have provided 45 two gussets, each having gores such as 15 and 16, since the said strip or strips when applied to the garment draw or support the same, and particularly the gussets 15, 16 into a pocket inclosing the organs.

50 My invention also comprehends the employment of a suitable pocket-forming or body-adjusting strip or tape, secured to the crotch portion of the garment at the front thereof and preferably, though not necessarily to the outside, and extending generally transversely of the garment. I have herein represented the said strip or tape in Figs. 1, 2 and 5 at 19, it being seamed or otherwise suitably secured as indicated at 55 20 transversely across the said gores 15, 16, and preferably to the leg portions of the garment at the right and left of said gores. While I have shown the said strip as attached along a curved line, it is apparent 60 65 that it may be attached in any suitable man-

ner and along any suitable extent thereof. The strip may be of any suitable material, and is here shown as a woven band or tape having free ends. Within the scope and purpose of my invention, I may employ a 70 pocket-forming strip or tape that may itself be attached to the garment at the rear or sides thereof or at any other suitable point or points. It may, intermediate its point of attachment at the crotch and its point or 75 points of attachment above the crotch, be provided with adjusting means by which it may be increased or shortened in length. This may be accomplished by providing buckles or other takeup means, and if desired, but not preferably, the strip or tape 80 may be of or may contain elastic material. In the disclosed embodiment of the invention, however, I provide a coöperating strip or strips, secured to the garment above 85 the crotch portion thereof, and having depending portions for attachment to the pocket forming strip 19.

While the coöperating strip or strips may be secured to any suitable portion of the 90 garment and may be of any suitable character, I have herein represented two strips 21, 22 respectively attached to the rear of the garment at 23, 24, at substantially the upper end of the gussets 6, 7.

The coöperating strip or strips, herein represented as the strips 21, 22, may, as previously stated, be secured to any suitable part of the garment, but by securing them to the back or sides of the garment and providing depending portions, the organ-supporting pocket which is provided by the strip or tape 19 and the gores 15, 16 is preserved when the wearer is in a seated position with his body relaxed. If the coöperating tape or tapes were secured to the front of the garment there might be a tendency of the strip 19, when the wearer is seated and his body is relaxed, to so position itself as partially to destroy the effectiveness 100 of the pocket. It is, however, to be understood that the coöperating strips may be secured to any suitable portion of the garment and within the broader aspect of my invention I may, in certain cases, dispense 105 with the coöperating strip or strips and otherwise attach the strip 19, as for example by making the same of sufficient length to permit it to be passed about the waist of the wearer and suitably tied together at its ends.

The transversely positioned strip or tape 19, when drawn upward, as indicated most clearly in Fig. 5, so draws upon the crotch portion of the garment as to inclose the organs in a pocket and thus in effect to form a suspensory. In this function the gores 15, 16 effectively coöperate, and because of the double thickness of the material additional protection is provided and the pocket is 115 120 125 130 135

reinforced. Furthermore, the strip or tape 19 constitutes a body adjustment. That is to say, if the body portion of the garment be found not to fit the wearer perfectly but to be somewhat too long, it may be drawn up to fit the wearer snugly by drawing upon the ends of the tape 19, and conversely, if the body be somewhat too short, then by loosening the strip or tape 19, it may be somewhat lengthened.

Within the scope of my invention the strip or tape, or other supporting means, may be secured either to the inside or to the outside of the garment. While preferably I secure it to the outside of the garment, as represented in Figs. 1, 2 and 5, I have in Fig. 6 represented it as secured to the inside thereof. In such form or embodiment of my invention I have represented a short band 25, 20 of general rectangular form but having a cut-out portion 26. The said piece 25 is secured at its lower edge 27 only to the garment, transversely thereof, so as to provide a pocket between itself and the gores 15, 16. 25 Either integral with the piece 25 or attached thereto, I provide strip portions 28, 29, corresponding generally to the strip 19. The free ends of the strip portions 28, 29, are adapted to be held in place in any suitable 30 manner, as for example by attaching them to the free ends of strips 30, 31, which preferably are attached to the back of the garment in a manner similar to that shown in Fig. 2. They may, however, be attached in 35 any suitable manner.

It will be evident from the foregoing description that I have provided an undergarment having an organs-supporting pocket, the garment because of the provision 40 of the gussets 6, 7, with their gores 15, 16, being peculiarly adapted for the formation of such a pocket, and the elements coöperating with said gussets in the formation of the pocket being of such simple construction 45 that the garment may be readily adjusted. Furthermore, the means coöperating with the gussets constitutes a body adjustment.

Having thus described one illustrative embodiment of my invention, I desire it to be understood that although specific terms are employed, they are used in a generic and descriptive sense and not for purposes of limitation, the scope of the invention being set forth in the following claims.

55 Claims:

1. An undergarment for males having lower trunk, crotch and leg portions and a pocket-forming strip or tape secured to the crotch portion at the front of and extending 60 transversely of the garment, and having opposed-securings portions by which the secured portion of the strip or tape and the crotch portion may be lifted into pocket form.

65 2. An undergarment for males having

lower trunk, crotch and leg portions and an organs-pocket-forming strip or tape secured to the crotch portion below the organs at the front of and extending transversely of the garment and having opposed-securings portions by which the secured portion of the strip or tape and the crotch portion may be lifted into pocket form. 70

3. An undergarment for males having a crotch portion and having lower trunk 75 and leg portions, and one or more gusset portions at the front of the garment at the crotch thereof, and a pocket-forming strip or tape secured to a gusset portion and to the adjacent leg portions at the front of and 80 extending transversely of the garment and having opposed-securings portions, whereby the material of the gusset or gussets may be drawn up into a pocket inclosing the organs.

4. An undergarment for males having a 85 crotch portion and having lower trunk and leg portions, each leg at its upper portion having a gusset extending therefrom to the opposite leg portion, thereby to form a double thickness of material at the crotch, and a 90 pocket-forming strip or tape secured to one of said gusset portions at the front of and extending transversely of the garment and having opposed-securings portions, whereby the material of the gusset or gussets may be 95 drawn up into a pocket inclosing the organs.

5. An undergarment for males having a crotch portion and having lower trunk and 100 leg portions, each leg at its upper portion having a gusset extending therefrom to the opposite leg portions, thereby to form a double thickness of material at the crotch, the upper portions of said gussets being superimposed and the upper ends of said gussets being both at one and the same side of 105 the axial line of the garment, whereby pocket-forming material is provided at one side of the axial line of the garment, and a pocket-forming strip or tape secured to a 110 gusset portion and to the adjacent leg portions at the front of and extending transversely of the garment and having opposed-securings portions, whereby the material of the gusset or gussets may be drawn up into 115 a pocket inclosing the organs.

6. A union undergarment for males having a crotch portion and having a pocket-forming strip or tape secured to the crotch portion at the front of and extending transversely of the garment, and having opposed-securings portions by which the secured portion of the strip or tape and the crotch portion may be lifted into pocket form. 120

7. A union undergarment for males having a crotch portion and having a pocket-forming strip or tape secured to the crotch portion at the front of and extending transversely of the garment, and having terminal-securings portions by which the secured 125 portion of the strip or tape and the crotch portion may be lifted into pocket form.

65 2. An undergarment for males having

portion of the strip or tape and the crotch portion may be lifted into pocket form, and a coöperating strip or strips secured to the garment above the crotch portion thereof and having depending portions for attachment to the said terminal-securing portions.

8. A union undergarment for males having a crotch portion and having a pocket-forming strip or tape secured to the crotch portion at the front of and extending transversely of the garment, and having terminal-securing portions by which the secured portion of the strip or tape and the crotch portion may be lifted into pocket form, and 10 a coöperating strip or strips secured to the rear of the garment and having depending portions for attachment to the said terminal-securing portions, the position of the coöperating strip or strips being such that 15 20 when said portions are attached and the user is seated, the bag formation is wholly retained.

9. A union undergarment for males having a crotch portion and having a pocket-forming strip or tape secured to the crotch portion at the front of and extending transversely of the garment, and having terminal-securing portions by which the secured portion of the strip or tape and the crotch portion may be lifted into pocket form, and a 25 coöperating strip or strips secured to the rear of the garment at substantially the small of the back and having depending portions for attachment to the said terminal-30 securing portions, the position of the coöp-35

erating strip or strips being such that when said depending portions are attached and the user is seated, the pocket formation is wholly retained.

10. An undergarment for males having a crotch portion and having a lower trunk portion 1 and leg portions 3—3, each leg at its upper portion having a gusset 6, 7 extending therefrom to the opposite leg portion, thus forming a double thickness of material at the crotch, the upper portions 15, 16 of said gussets being superimposed, a pocket forming strip or tape 19 secured to a gusset portion and to the adjacent leg portions at the front of and extending transversely of the garment and having opposed securing portions and strips 21, 22 secured to the garment and adapted to be secured to the ends of the strip or tape 19. 40 45 50

11. An undergarment having lower trunk, 55 crotch and leg portions, and a trunk-adjusting strip or tape secured to the crotch portion at the front of and extending transversely the garment and having opposed securing portions by means of which the 60 trunk portion may be adjusted to the proper height.

In testimony whereof I have signed my name to this specification, in the presence of two subscribing witnesses.
